GRAMOPHONE AND THE LIKE

Application filed February 5, 1929, Serial No. 337,660, and in Great Britain February 6, 1928.

This invention relates to improvements in gramophones and the like, and refers particularly to instruments of the type in which mechanical vibrations set up in a stylus bar travelling over a record disc are converted into electrical vibrations by what is known as an "electrical pick-up", amplified, and distributed as sound waves by a loud-speaker.

In the ordinary type of gramophone employing a sound-box, the sound-box is carried at the free end of a swivelling hollow tone-arm, and as the tone-arm is necessarily comparatively short the path of the needle carried by the sound-box is not truly radial with respect to the disc but is an arc of a circle having the tone-arm as radius. It follows therefore that the sound-box and needle can only be in correct alignment with the groove in the record disc at one point, generally about the middle of the length of the groove, and excessive wear of the record is caused towards the outer and inner edges of the record disc by side-thrust of the needle in the groove.

The object of our invention is to provide means whereby in the case of an electrical pick-up this defect can be entirely eliminated so that wear on the record disc is reduced to a minimum and substantially true reproduction can be obtained without scratch or distortion.

A further object is to eliminate or reduce to the shortest possible length the usual loose leads between the pick-up and fixed terminals or other contacts on the gramophone body.

A still further object is to permit the weight of the pick-up itself to be counterbalanced or compensated for to any desired extent so that the weight applied to the stylus can be kept down to the minimum required to give correct reproduction and excessive wear of the record discs, which is a common fault with pick-ups, is eliminated.

These and other features of our invention will be made clear in the particular description with respect to the accompanying drawings in which:—

Figure 1 is a side elevation of one form 50 of pick-up mounting in accordance with our

invention which can be fitted to any existing gramophone.

Figure 2 is an end elevation.

Figure 3 is a section on the line 3—3 of Fig. 1 with the lug which carries the pick-up 55 raised, and the pick-up detached.

Figure 4 is a diagrammatic side elevation of a simple form of mounting for cheaper production.

Figure 5 is a similar side elevation of a 60 slightly heavier model.

Figure 6 is a side elevation of a mounting similar to that shown in Fig. 1; but with certain parts made of insulating material.

In the form illustrated in Figs. 1, 2 and 3, 65 the fixed part of the mounting consists of a cranked arm 1 of aluminium or like material having at one end a peg 2 of triangular or other section adapted to fit into and be secured in a bracket 3 secured upon the body of a gramophone. The free end of the arm extends horizontally over the gramophone turn-table and secured into it are small brackets 4 and 5, in which are mounted grooved rollers 6, 7, in point-pivot or other anti-friction bearings. The bracket 4 is secured directly into the arm but the bracket 5 is secured into an insulating bush in the arm for the reasons given below.

The pick-up 8 which is of any standard type has a bayonet or other connection with a socket at the free end of a metal lug 9 which terminates at its other end in a disc 10. The disc is clamped between discs 11 and 12 at the ends of two lengths of accurately machined cylindrical metal rod 13 and 13' by means of studs 14. A washer of insulating material is placed between the discs 10 and 12 and the studs 14 pass through insulating bushes so that the lug 9 is in metallic connection with the part 13 of the rod and insulated from the part 13'. These two parts of the rod are in exact alignment so that in effect they form mechanically one continuous rod. 95

The rod is adapted to rest in the grooves in the rollers 6 and 7 and is held against removal by stirrups 15 which are out of contact with the rod. The total length of the rod is such that throughout the entire range 100

of movement of the pick-up the rod is supported by both rollers.

For changing the needle or stylus 16 of the pick-up, the pick-up, lug, and rod can be 5 wung up around the axis of the rod into the position shown in Fig. 3 in which position it may be supported by a stop 17 on the lug which engages the rear edge of the arm.

Of the current leads from the pick-up one 10 is earthed on the metal socket as shown at 18 in Fig. 3. The circuit of this lead is then through the lug 9 to the rod 13 and through the roller 6 with which the rod is in metallic contact and so to the arm 1 and to a fixed terminal 19 thereon.

The other lead 20 is taken through a bore 15 in the lug 9 to a stud 21 in metallic contact with the rod 13'. This rod is in metallic contact with the roller 7 on the insulated bracket 20 from which an insulated wire is taken through a bore in the arm 1 to an insulated terminal 22 adjacent to the terminal 19. By this arrangement the usual loose leads are 25 eliminated and an extremely neat result is produced.

When applying this mounting to an existing gramophone a template is preferably 30 provided fitting over the centre pin of the turn-table and giving the exact location of the fixing screws for the base bracket 3. When the arm 1 is dropped into this bracket the rod 13 will lie in a position parallel to a radius 35 of the turn-table and at such a distance therefrom that the needle or stylus on the pick-up when in engagement with a record disc is constrained to move in a truly radial path thereon through the simple gravitational engagement of the rod in the grooves of the rollers. While this relation exists no other 40 movement is possible except a rolling or rotational movement about the axis of the rod which movement is permitted with a minimum of friction so that the pivotal action of the pick-up which allows it to ride freely 45 over any irregularities or inaccuracies of the record disc is obtained in the simplest possible manner.

If it should be found that the load on the 50 stylus imposed by the weight of the pick-up is greater than is necessary for good reproduction, the rod can be provided with counter-balance weights which may be carried on an extension of the lug 9, as shown in Fig. 3.

The embodiment illustrated in Fig. 4 is a 55 somewhat simpler form intended for easy application to existing gramophones. In this case a rod 23 is secured at its ends in lugs projecting forwardly from a rigid horizontal 60 arm 24 adjustably clamped on a fixed pillar. The pick-up is held in a clip on the end of an arm on a bifurcated bracket 25 on the arms of which are mounted grooved anti-friction rollers 25' adapted to travel on the rod. 65 Flexible electric leads from the pick-up are

taken to insulated terminals which may be mounted on the base of the fixed pillar.

In the modification illustrated diagrammatically in Fig. 5 a similar construction is employed and the rod is divided into two insulated sections which act as current leads. One of the rollers 26 is conveniently insulated 70 from the bracket 25 and an insulated lead is taken to the roller from the pick-up through a bore in the bracket. 75

The embodiment illustrated in Fig. 6 is similar to that illustrated in Fig. 1 but in this case the lug 9 is replaced by a lug 27 of moulded insulating material having a socket 80 at its outer end to receive the pick-up. Into the other end of the lug are moulded heads 28 on the inner ends of two machined cylindrical rods 29 which are rigidly held in alignment during the moulding process.

The arm 30 which replaces the arm 1 is 85 also moulded from insulating material and the brackets 31 carrying the grooved rollers 32 are secured into place in the moulding operation. Leads from the pick-up 8 are taken to terminals 33 which are connected 90 by internal leads 34 to the heads 28 on the rods. Each rod is in metallic contact with one roller 32 and hence with one bracket 31, and leads 35 are taken inside the arm 30 from the brackets 31 to fixed terminals 36 on the arm 30 near its anchored end. 95

We claim:

1. A mounting for an electrical pick-up for gramophones comprising a fixed support, a holder for the pick-up, and travelling connection means between the support and the holder, said means constraining said support to travel in a path parallel to a radius of a record disc through the point of contact with the disc of a stylus carried by the pick-up and said means permitting the support to be rocked in a plane at right angles to its line of travel. 100

2. A mounting for an electrical pick-up for gramophones comprising a fixed support, a holder for a pick-up, and travelling connection means between the support and the holder formed by the co-engagement of spaced grooved rollers with a straight cylindrical rod, which permits the holder to rock about the axis of the rod and constrains it to travel in a straight line parallel to a radius of a record disc passing through the point of contact with the disc of a stylus carried by the pick-up. 110

3. A mounting for an electrical pick-up for gramophones comprising a fixed supporting arm, a fixed cylindrical rod carried by said arm, a holder for a pick-up, and spaced grooved rollers on said holder adapted to travel along said cylindrical rod and to allow the holder to be rotated about the axis of the rod, the said rod being parallel to a radius of a record disc passing through 125 130

the point of contact with the disc of a stylus carried by the pick-up.

4. A mounting for an electrical pick-up for gramophones comprising a fixed support, a holder for a pick-up, and travelling connection means between the support and the holder formed by the co-engagement of spaced grooved rollers with a straight cylindrical rod, said rod being divided transversely into two portions which are electrically insulated from each other and are employed as conductors in an electrical circuit leading from the pick-up to fixed terminals on the support.

15 5. A mounting for an electrical pick-up for gramophones comprising a fixed support, a holder for a pick-up, and travelling connection means between the support and the holder formed by the co-engagement of 20 spaced grooved rollers with a straight cylindrical rod which permits the holder to rock about the axis of the rod and constrains it to travel in a straight line parallel to a radius of a record disc passing through the 25 point of contact with the disc of a stylus carried by the pick-up, an extension on said holder extending on the side of the rod opposite from the pick-up, and adjustable means on said extension to compensate for 30 the weight of the pick-up.

In testimony whereof we affix our signatures.

CECIL MONTAGUE WALTER.
RICHARD GREGORY MARSH.
